CHARLES I. EARLL, OF NEW YORK, N. Y.

TROLLEY-RETRIEVER.

1,110,736.

Specification of Letters Patent. Patented Sept. 15, 1914.

Application filed September 18, 1907. Serial No. 892,783.

To all whom it may concern:

Be it known that I, CHARLES I. EARLL, a citizen of the United States of America, and resident of the city, county, and State of New York, have invented certain new and useful Improvements in Trolley-Retrievers, of which the following is a specification.

My invention relates to trolley retrievers.

In devices of this class there is a drum 10 adapted to receive the trolley rope, a relatively light spring adapted to act upon the drum to cause it to take up the slack in the trolley rope and to produce only a slight tension therein, a heavy power or retrieving spring normally in a set or strained condition and adapted to be put into action automatically to rotate the drum and wind up the rope thereon and thus pull the trolley down when the trolley jumps the wire. The 20 power spring relaxes or unwinds in the act of pulling down the trolley and in order to restore it to its normal condition so that it will be ready when called upon to act again, it is necessary to rewind or reset it. 25 This is usually accomplished by pulling out the rope from the retriever, against the action of the power spring, means being provided to hold one end of the spring against rotation and to cause the other end to turn 30 with the drum while the rope is being pulled out from the retriever. In some retrievers the amount or degree to which the power spring is wound up is left to the judgment of the operator, who may wind it up much 35 or little or not at all; in others the power spring must be wound up to a predetermined amount or degree before the trolley rope can be released so as to operate freely under the action of the tension spring.

40 My present invention relates more particularly to the second class of retrievers which may be termed the class of compulsory-set retrievers. This class of retrievers has the advantage that the conductor or operator 45 cannot neglect to properly reset or rewind the power spring and thus run the retriever in an inoperative condition. The power required to pull the trolley down varies greatly on different trolley roads. In some 50 instances the pressure of the trolley upon the trolley wire is as low as twelve to sixteen pounds; in others it is as high as forty-five to fifty pounds. Heretofore it has been necessary to provide power springs of different strengths to meet the various requirements. Again, the power springs frequently

weaken after they have been in service for some time, when it is necessary to replace them with new ones.

It is one of the objects of my invention 60 to produce means in a compulsory-set retriever, whereby the amount which it is necessary to wind up the power spring may be adjusted by merely changing the relation of certain parts without the necessity of substituting different power springs or other parts.

65 Retrievers are especially useful for cars operated at high speeds and in order to be effective in preventing the trolley from 70 striking the overhead structure when it jumps from the wire the retriever must act very quickly. To do this a power spring must be provided of sufficient strength to 75 overcome the inertia of the trolley pole and trolley wheel and pull them down to a safe distance below the overhead structure in a very short interval of time, during which the trolley acquires a momentum which carries it to a point below that at which the 80 power spring of the retriever and the trolley base springs which press the pole upward and oppose the power spring of the retrievers, are in equilibrium, and there is a 85 tendency for the pole to rebound upward.

90 It is one of the objects of my invention to provide means which shall operate to prevent or retard the tendency of the trolley to rebound after it has been retrieved.

Another object of my invention is to 95 provide a trolley retriever which shall be especially simple and effective in its construction and operation.

95 My invention consists in the novel construction and arrangements hereinafter illustrated and described and particularly set forth in the claims.

In the drawings accompanying and forming a part of this specification, Figure 1 is a central section through the axis of the 100 shaft on which the drum rotates, taken on line *a*—*a* of Fig. 2. Fig. 2 is a rear view showing the back sectioned on line *b*—*b* of Fig. 1 and the other parts unsectioned. Fig. 3 is a view similar to Fig. 2 showing all the 105 parts in section on line *b*—*b* of Fig. 1.

The reference characters are used in the same sense throughout the drawings and specifications.

110 Numeral 1 represents the back and 2 the front part of the case, 3 the drum on which the trolley rope is wound, 4 the shaft on

which the drum rotates, 5 a disk or plate secured to the shaft, 6 a thumb nut on the end of the shaft opposite to the plate 5, 7 a tension spring which is secured to the drum at its outer end and to the inwardly projecting hub of the plate 5 at its inner end, 8 a power spring the outer end of which is secured to the drum and the inner end to the hub 9 of the intermediate member 10. The disk 5, the shaft 4 to which it is secured, and the thumb nut 6, serve to clamp the shell 2 and the back 1 together; and these parts also serve to hold and adjust the inner end of the tension spring. The intermediate member 10 has three studs or journals, 11, 12, and 13, respectively, made integral with or secured to it. The lock pawl 14 is pivotally mounted on the stud 11, the bell crank 15 on the stud 12, and the set pawl 16 on the stud 13. A centrifugal pawl 17 is pivotally secured to the lock pawl 14. The tension spring being connected at its inner end to the inwardly projecting hub of the plate 5, which is stationary, and at its outer end to the drum, tends to rotate the drum in the direction opposite to the arrow *c* with a power only sufficient to take up the slack in the trolley rope 18, and to permit the rope to be drawn out under slight tension as the trolley pole rises and falls due to the varying height of the trolley wire above the tracks. The power spring or retrieving spring, 8, having its outer end secured to the drum and its inner end to the hub 9 of the intermediate member 10, tends when wound up, to rotate the drum in the direction opposite to arrow *c*, that is, in the direction to wind up trolley rope on the drum, and to rotate the intermediate member in the opposite direction. The drum is provided with an annular flange having teeth 19 formed thereon, which project outwardly from the face of the drum into the plane occupied by the lock pawl 14, the bell crank 15, the set pawl 16 and the centrifugal pawl 17. The lock pawl 14 is adapted to engage the teeth 19 of the drum to prevent the unwinding of the power spring, and it is also adapted to engage the teeth 20 of the back 1 to lock the intermediate member to the back and prevent it from turning under the action of the power spring. It will therefore be obvious that, when the power spring is wound up and the lock pawl engages a tooth 19 of the drum, the intermediate member and the drum will rotate together and the power spring will have no effect upon the rotation of either; it will also be obvious that, when the lock pawl is released from the drum and engages a tooth in the back, the power spring will exert its full effect in tending to rotate the drum in a direction opposite to the arrow *c*, that is, in the direction to wind up the trolley rope 18 on the drum. The strength of the power

spring is sufficient to overcome the upward pull of the trolley.

When the power spring has been wound up to the predetermined degree for which the retriever has been adjusted, the parts will occupy the positions shown in Fig. 2; the lock pawl 14, the centrifugal pawl 17 and the set pawl 16 will all be in their inner positions and will revolve with the drum clear of the teeth 20 formed in the back 1. The drum will then rotate freely back and forth under the action of the tension spring 7, as the trolley rises and falls due to the varying height of the trolley wire.

The spring 21 secured to the lug 22 on the centrifugal pawl and to the lug 23 on the intermediate member, tends to hold the centrifugal pawl against the drum, and also to keep the lock pawl 14 in engagement with the teeth 19 on the drum while the power spring is being wound up. When the trolley jumps the wire the sudden rotation imparted to the drum in the direction of the arrow *c* Fig. 2, causes the centrifugal pawl 17 to fly outward and engage one of the teeth 20 in the back. The continued movement of the drum after such engagement forces the lock pawl 14 out of engagement with the drum and into engagement with one of the teeth 20 of the back, thereby releasing the intermediate member from the drum and locking it to the back. This operation releases the power spring and puts it into retrieving action to rotate the drum and wind up the trolley rope and pull the pole down. As the lock pawl 14 passes into full engagement with the teeth 20 of the back, the centrifugal pawl 17 is lifted slightly out of engagement with the teeth of the back and brought back to the teeth of the drum by the spring 21. The centrifugal pawl 17 is provided with a hook tooth 24 at its end adapted to engage the teeth 19 when the lock pawl engages the teeth 20, the purpose of which is to pull the lock pawl 14 out of engagement with the teeth 20 of the back at the first turning of the drum in the direction of arrow *c* after retrieving action has taken place, i. e.: when the operator starts to pull out the rope to rewind the power spring. As soon as the lock pawl is released from the tooth 20 the spring 21 will bring it into engagement with the teeth 19 on the drum. While the drum is rotating during the retrieving action (in the direction opposite to the arrow *c*) the hook tooth 24 at the end of the centrifugal pawl will ride over the teeth 19 of the drum, the centrifugal pawl being held elastically against said teeth by the spring 21. The centrifugal pawl 17 is provided with a flange 25 having a cam surface 44 formed thereon, which extends over the teeth 19 on the drum, the contour of this cam surface and flange being

80

such as to prevent the engagement of the hook tooth 24 with the teeth 19 when, after the lock pawl 14 has been restored to engagement with the teeth 19 of the drum as above described and the intermediate member is held from rotating by means presently to be described, the drum is rotated in the direction of the arrow *c* by pulling out the trolley rope to rewind the power spring.

10 When the retrieving action has taken place and the lock pawl has been restored to engagement with the teeth 19 on the drum by a pull on the trolley rope, as above described, it is necessary to provide some other 15 retaining means than the lock pawl to prevent the intermediate member from turning (in the direction of the arrow *c*) while the rope is being pulled out to rewind the power spring, as otherwise the intermediate member 20 would turn with the drum and it would be impossible to wind the spring. This means consists of the set pawl 16 and the parts which control and operate in conjunction with it, including means to limit 25 the winding of the power spring, which I will now describe. A controller 30, preferably made of flat spring steel, having a curled end formed to fit a hole 27 in the drum and having its free end 31 resting 30 upon and pressing inwardly against the outer coil of the power spring 8, extends outwardly beyond the face of the power spring into the plane of the controller ratchet 32. The controller is so formed as to 35 press elastically against the outer coil of the power spring, and I prefer to make it of such form and material that one end may be secured fixedly to the drum while by virtue of its own elasticity the other end will maintain 40 its engagement with the power spring and at the same time have sufficient strength to operate the controller ratchet 32; it is obvious, however, that the detailed construction of the controller may be varied without 45 departing from the scope of my invention, the essential characteristic of the controller being that it is a member elastically pressed against the outer coil of the power spring, so that it will move inwardly as the power 50 spring is wound up and move outwardly as said spring unwinds and by such movements be brought into and out of engaging position to operate the desired elements of the mechanism at a certain time in the winding 55 or unwinding, as the case may be, of said power spring. When the power spring is relaxed it will expand until it fills the opening in the drum, and in doing this it will force the controller 30 outward against the 60 inner periphery of the drum and out of engagement with the controller ratchet 32; as the power spring is wound up the coil will decrease in diameter and the end 31 of the controller 30 will follow in and engage one 65 of the teeth of the ratchet 32, and the con-

troller being carried by the drum will partake of the rotative movement of the drum during the winding of the power spring and thereby actuate the controlled ratchet. The controller ratchet 32 is rotatably mounted 70 on the hub of the disk 38. The disk 38 is secured in the end of the drum between the power spring 8 and the intermediate member 10 and it has a portion, indicated by the dotted lines 40 Fig. 2, cut away to permit 75 the controller to extend through said cut away portion to engage the ratchet 32. The ratchet 32 is provided with a lug 33 adapted to engage the arm 34 of the bell crank 15, so that as the ratchet 32 is turned by the controller 30, the lug 33 will rotate the bell crank causing the bell crank to come into engagement with one of the teeth 19 on the drum, thereby preventing the further turning 80 of the drum and winding up of the 85 power spring.

When the parts are in their normal positions, with the power spring wound up, as in Fig. 2, the controller is in engagement with the ratchet 32, which it holds in the position in which the engagement of the lug 33 with the arm 34 of the bell crank holds the arm 15 of the bell crank in its inner position. The spring 35 secured at one end to the set pawl 16, is coiled around the hub 90 of said set pawl and engages a lug 36 of the bell crank. This spring tends to press the end 37 of the set pawl against the arm 15 of the bell crank, the end 37 being extended so that it will contact the arm 15 of the bell 95 crank between the lug 36 where the spring 35 engages the bell crank and the center of the stud 12, on which the bell crank is mounted. So long, therefore, as the bell crank is held by the controller ratchet and 100 the controller, in its inner position, the spring 35 will tend to keep the set pawl 16 in its inner position out of engagement with the teeth 20 of the back, at the same time, because of the fact that the point of contact 105 between the end 37 of the set pawl and the arm 15 is between the point of application or engagement of the spring 35 with the lug 36, and the stud 12, the spring 35 tends to turn the bell crank and the set pawl together 110 in the direction of the arrows *e* and *d* respectively and will so turn them when the controller ratchet is released from the controller, as takes place immediately after the lock pawl has been released from the drum 115 and the drum begins to rotate under the action of the power spring to wind up the trolley rope. When the controller ratchet is thus freed from the controller the spring 120 35 will cause the bell crank and set pawl to 125 turn together as above described until the set pawl engages the teeth 20 in the back. The set pawl will therefore hold the intermediate member from turning as rope is pulled out to rewind the power spring after 130

the retrieving action. When the power spring has been wound up to a predetermined amount the controller will follow in and engage the controller ratchet and turn 5 the same until the lug 33 engages and turns the bell crank to the position where the end of the arm 15 of the bell crank will engage a tooth 19 of the drum as shown in Fig. 3. The pressure of the end of the set pawl 10 against the tooth 20 which it engages during the rewinding of the power spring is such as to prevent the set pawl from being pulled away from the tooth 20 by the spring 35 until the pull on the rope is relaxed. As 15 the arm 15 of the bell crank makes contact with the tooth 19 of the drum at the completion of the winding up of the power spring, the lock pawl 14 will drop behind a tooth of the drum with a slight clearance, 20 then as the pull on the trolley rope is relaxed, the drum will rotate slightly to take up the clearance between the tooth 19 and the lock pawl and then the further relaxation of the pull on the trolley rope will 25 relieve the pressure on the set pawl and permit it to drop back to engagement with the bell crank under the action of the spring 35.

The end of the hub 39 of the drum has a 30 groove 41 formed in it and a spring 42 has one end formed to fit in this groove while the other end is secured by a lug 43 on the intermediate member. This spring 42 tends to force the intermediate member against 35 the drum and to produce a friction which resists the relative movement of the intermediate member and drum.

The purpose of creating a frictional resistance between the intermediate member 40 and the drum is to retard the tendency of the trolley to rebound after the retrieving action has taken place. I have found that a comparatively slight frictional resistance between these two members acts effectively 45 to prevent or materially reduce such rebound. At the same time it does not materially decrease the effectiveness of the retrieving spring in pulling the trolley down or materially increase the power required to 50 wind up the retrieving spring.

The operation of the mechanism is as follows: The parts are shown in a normal position with the power spring wound up in Fig. 2. When there is a sudden pull on the 55 trolley rope, as when the trolley jumps the wire, the drum is rapidly rotated in the direction of the arrow *c* Fig. 2; the centrifugal pawl 17 is thrown out until it engages one of the teeth 20 in the back; this engagement forces the lock pawl 14 out of engagement with a tooth 19 on the drum and into engagement with a tooth 20 in the back; the intermediate member is then unlocked from the drum and the power spring turns the 60 drum in a direction opposite to the arrow *c* 65

and winds up the trolley rope and pulls the trolley down. During this operation, while the lock pawl 14 is still in engagement with the tooth 20, the free end of the centrifugal pawl has dropped back to an engaging position with the teeth of the drum. 70

During the unwinding or relaxation of the power spring, which takes place while the trolley is being pulled down, it expands and the end 31 of the controller is forced 75 out of engagement with the controller ratchet. As soon as the controller ratchet is freed from the controller, the action of the spring 35, connecting the set pawl 16 and the bell crank 15, will force the set pawl out 80 into engagement with the teeth 20. Then as soon as rope is pulled out from the retriever the engagement of the hook 24 of the centrifugal pawl with one of the teeth 19 of the drum will pull the lock pawl out 85 of engagement with the teeth 20 and the engagement of the set pawl 16 with the teeth 20 will prevent the intermediate member from turning so that as the rope is further pulled out from the retriever the effect will 90 be to rewind the power spring. If the trolley rope is pulled down before the power spring is fully rewound, the engagement of the lock pawl 14 with the teeth 19 will prevent the power spring from unwinding and 95 the drum and intermediate member will turn together in the direction opposite to the arrow *c*, the set pawl riding backward over the teeth 20. In this way the power spring may be wound up by reciprocating 100 the rope up and down or back and forth into and out of the retriever. When the power spring has been wound up to an amount or degree which permits the controller 30 to engage the ratchet 32, the turning of the 105 ratchet 32 will cause the lug 33 on said ratchet to bring the bell crank to the position shown in Fig. 3 where its end will strike one of the teeth 19 of the drum and act as a stop to prevent the further winding 110 or setting of the power spring. At this point the lock pawl 14 drops in between the teeth on the drum with a slight clearance as shown in Fig. 3; then when the pull on the trolley rope is relaxed this clearance will be 115 taken up, the lock pawl will engage the tooth and hold the power spring from unwinding and the set pawl, as soon as the pressure between it and the tooth 20 which it engages is relieved, will drop back to its normal position on the bell crank. The outer coil of the power spring while it is being wound up is eccentric to the hub of the intermediate member and to the cylindrical recess which it occupies so that the amount or degree to 120 which the power spring must be wound up in order to permit the controller to follow in and engage the controller ratchet, depends upon the location of the controller. 125

By shifting the position of the controller, I. 130

am thus enabled to change or vary and adjust the amount to which the power spring must be wound up before the controller ratchet will be operated. In practice I generally provide four holes, as 26, 27, 28 and 29, into any one of which the coiled end of the controller may be inserted and each giving a different action of power spring.

Having thus described my invention, 10 what I claim is:

1. In a trolley retriever the combination with two relatively movable members one constituting a drum and the other a normally stationary member; an intermediate member and a power spring secured to said intermediate member and to one of the other of said members, of a ratchet and pawl connection between said intermediate member and the other of said members to which said power spring is attached, and means actuated by turning the drum in a direction to wind up the power spring to bring said ratchet and pawl connection into engagement.
2. In a trolley retriever, the combination with two relatively movable members consisting respectively of a drum adapted to receive the trolley rope and a normally stationary member, of an intermediate member, a power spring connecting said intermediate member with one and a releasable lock connecting it with the other of said relatively movable members during the winding of the power spring, of a stop mechanism adapted to limit the amount to which said power spring may be wound up, and means mounted on the member to which the outer end of said power spring is connected engaging said power spring intermediate its ends to actuate the said stop mechanism.
3. In a trolley retriever the combination with two relatively movable members consisting respectively of a drum adapted to receive the trolley rope and a normally stationary member, an intermediate member, a power spring connecting said intermediate member with one and a releasable lock connecting it with the other of said relatively movable members during the winding of said power spring, of a lock releasing mechanism adapted to release said releasable lock, and means mounted on the member to which the outer end of said power spring is connected engaging said power spring intermediate its ends to operate said lock releasing mechanism.
4. In a trolley retriever the combination with two relatively rotatable members and a retrieving spring connecting said members, of means adapted to press said relatively rotatable members together with a predetermined pressure to produce a frictional resistance to their relative rotation.
5. In a trolley retriever the combination with two relatively rotatable members con-

sisting respectively of a drum adapted to receive the trolley rope and a normally stationary member, and a rotatable intermediate member, of a power spring connecting said intermediate member with one of said relatively rotatable members, a locking mechanism adapted in its normal position to lock said intermediate member to the one of said relatively rotatable members to which said power spring is connected to retain the spring from unwinding, and to lock said intermediate member to the other relatively rotatable member to put the power spring into retrieving action, the said locking mechanism including means engaged by the drum to restore said locking mechanism to its normal position when the drum is first turned in the direction to unwind rope therefrom after said retrieving action.

6. In a trolley retriever the combination with a case provided with internal teeth, of a drum provided with teeth and an intermediate member concentrically and rotatably mounted in said case, a retrieving spring secured to said drum and to said intermediate member, a lock pawl mounted on said intermediate member adapted to engage alternately the teeth in said case and the teeth on said drum and a centrifugal pawl mounted on said lock pawl having a hook tooth adapted to engage the teeth on said drum when the lock pawl is in engagement with said case and a surface which engages said drum and prevents the engagement of said hook tooth with said teeth when the lock pawl is in engagement with said teeth on said drum.

7. The combination with a spiral spring and an inclosing drum and means for winding the spring of a member mounted in said drum engaging a coil of said spring and adapted to follow inwardly toward the center of said spring as said spring is being wound up.

8. The combination with two relatively rotatable members and the spiral spring having its outer end connected to one and its inner end to the other of said members so that their relative rotation winds or unwinds said spring, of a member mounted on the member to which the outer end of said spring is connected adapted to press elastically against the outer coil of said spring and thereby to remove inwardly as said spring is wound up.

9. The combination with two relatively rotatable members of a spiral spring having its inner end attached to one and its outer end to the other of said members, and a controller mounted on one of said rotatable members adapted to press inwardly against the outer coil of said spring whereby it is moved into its operative position by its engagement with said spring.

10. The combination with two relatively

70

75

80

85

90

95

100

105

110

115

120

125

130

rotatable members, of a spiral spring having its inner end attached to one and its outer end to the other of said members, and a spring pawl mounted on one of said members and adapted to press elastically against the outer coil of said spiral spring.

11. The combination with two relatively rotatable members, of a spiral spring having its outer end connected to one and its inner 10 end to the other of said relatively rotatable members, a stop mechanism mounted on one and adapted to engage the other of said members to limit the winding of said spring, and a controller mounted on one of said 15 members and engaging a coil of said spring and adapted to operate said stop mechanism.

12. A lock pawl for trolley retrievers having a hole adapted to receive a stud at one end and a centrifugal pawl provided with 20 an abutting end and a hook, pivotally secured near its other end.

13. In a trolley retriever the combination with a retrieving spring, a member secured to the outer end and a member secured to the 25 inner end of said retrieving spring, a lever mounted on said second member, a ratchet provided with a lug adapted to engage said lever and a controller mounted on said first member adapted to engage said power 30 spring intermediate its ends and to engage said ratchet when said power spring is wound up a predetermined amount.

14. In a trolley retriever the combination with a drum, a retrieving spring and a retrieving 35 spring retaining mechanism adapted to retain the retrieving spring at intervals while it is being wound up, of a connection between said retaining mechanism and the drum for throwing the retaining mechanism into action, actuated by the turning of 40 the drum in the direction to wind up said spring.

15. In a trolley retriever the combination with a case provided with internal teeth, a 45 drum, an intermediate member and a retrieving spring connecting said drum and said intermediate member, of a lock mounted on said intermediate member adapted to alternately engage said case and said drum and a 50 centrifugal pawl connected with said lock adapted to engage said case to release the lock from the drum and to engage the drum to release the lock from the case.

16. The combination with a pair of pawls 55 mounted on pivots at a distance apart less than the combined lengths of said pawls, one of said pawls being adapted to engage the other at a point between its end and its pivot, of a spring tending to press said 60 pawls together secured to one and engaging the other of said pawls at a point removed from the point of contact between said pawls, whereby the pawls may be separated against the action of said spring, and when

in contact said spring tends to turn them in 65 opposite directions.

17. In a trolley retriever the combination with a drum and a power spring adapted to be wound up by the turning of the drum, of a stop mechanism to limit the winding of 70 said power spring, and a controller adapted to actuate said stop mechanism mounted in fixed relation to the outer end and elastically engaging the outer coil of said power spring.

18. In a trolley retriever the combination 75 with a drum, a tension spring and a power spring, of a controller mounted a fixed distance from the outer end of the power spring adapted to engage a coil of said power spring intermediate its two ends and 80 means engaging said controller to limit the winding of said power spring.

19. In a trolley retriever the combination with three relatively rotatable members one constituting a drum for the trolley rope, 85 another a normally stationary member, and the other an intermediate member; and a retrieving spring having one end secured to said intermediate member and the other end to one of the other of said members, connections between said intermediate member 90 and the member not attached to the retrieving spring adapted to lock said intermediate member and said member together during the winding of the spring, and a controller mounted on the member to which the outer end of the retrieving spring is secured, and 95 pressed elastically against a coil of said spring and means engaging said connections and engaged by said controller adapted to cause the disengagement of said connections when said retrieving spring has been wound a predetermined amount.

20. In a trolley retriever the combination with a drum, a stationary member, an intermediate member, and a power spring secured to said intermediate member and to 100 said drum, of a ratchet and pawl connection between said intermediate member and said drum and means actuated by the turning of the drum in the direction to wind up the power spring to bring said ratchet and pawl connection into engagement.

21. In a trolley retriever the combination with a drum, a stationary member, an intermediate member, a power spring connecting said intermediate member with said drum and a releasable lock connecting said intermediate member with said stationary member during the winding of the power spring, 115 of a stop mechanism adapted to limit the amount to which said power spring may be wound up, and means mounted on said drum 120 engaging said power spring intermediate its ends adapted to actuate said stop mechanism.

22. In a trolley retriever the combination with a drum a stationary member, an inter- 125

mediate member and a releasable lock adapted to connect said intermediate member with said stationary member during the winding of said power spring, of a lock releasing mechanism adapted to release said releasable lock, and means mounted on said drum engaging said power spring intermediate its ends adapted to operate said releasing mechanism.

10 23. In a trolley retriever the combination with a case provided with internal teeth, of a drum provided with teeth and an intermediate member concentrically and rotatably mounted in said case, a retrieving spring secured to said drum and to said intermediate member, a lock pawl mounted on said intermediate member and adapted to engage alternately the teeth in said case and the teeth on said drum, and a centrifugal 20 pawl pivotally mounted on said lock pawl adapted to engage the teeth on said drum when the lock pawl is in engagement with the teeth in said case and to release said lock pawl from the teeth in said case when the 25 drum is turned in the direction to unwind rope therefrom.

24. In a trolley retriever the combination with a case, of a drum and an intermediate member rotatably mounted in said case, a retrieving spring connecting said drum and

said intermediate member, a lever pivotally mounted on said intermediate member and adapted to engage said drum to oppose the relative rotation of said intermediate member and said drum, a ratchet wheel having a 35 lug adapted to engage said lever mounted concentrically with said drum and a controller mounted in said drum engaging said retrieving spring intermediate its ends and adapted to engage and actuate said ratchet 40 wheel when said retrieving spring has been wound up a predetermined amount.

25. In a trolley retriever the combination of a casing, a retrieving spring mounted therein, a slack-absorbing spring in the casing, a rotatable trolley rope reel, means for winding and locking the retrieving spring against action, the winding operation being effected by the unwinding of the trolley rope from said trolley rope reel, and means elastically engaging the outer coil of said retrieving spring for limiting the winding of said spring.

In testimony whereof, I have signed my name to this specification in the presence of 55 two subscribing witnesses.

CHARLES I. EARLL.
